Primary Examiner—Marcus A. Jackson

(**) Term: **14 Years**

(57) **CLAIM**

(21) Appl. No.: **29/127,433**

The ornamental design for a headlight divider signal light lens, as shown and described.

(22) Filed: **Aug. 6, 2000**

DESCRIPTION

(51) LOC (7) Cl. **26-99**

FIG. 1 is a top frontal isometric view showing my new design of the headlight divider signal light lens position on a passenger automobile, the opposite side of the automobile comprising a mirror image;

(52) U.S. Cl. **D26/139**

FIG. 2 is a top frontal isometric view of the design, the opposite side of the automobile comprising a mirror image;

(58) Field of Search D26/28-36, 139;

FIG. 3 is a bottom isometric view of the design, the opposite side of the automobile comprising a mirror image;

362/61, 80, 80.1, 81, 82, 83, 83.2, 83.3,
290, 325, 344, 364, 376

FIG. 4 is a top plan view, the opposite side of the automobile comprising a mirror image;

(56) **References Cited**

FIG. 5 is a left end elevation view thereof, the opposite side of the automobile comprising a mirror image;

U.S. PATENT DOCUMENTS

FIG. 6 is a right end elevation view thereof, the opposite side of the automobile comprising a mirror image;
